(57) **CLAIM**

The ornamental design for a hydrant bonnet sleeve, as shown and described.

DESCRIPTION

FIG. 1 is a top perspective view of a hydrant bonnet sleeve showing my new design;

FIG. 2 is a bottom perspective view of FIG. 1;

FIG. 3 is a top plan view of FIG. 1;

FIG. 4 is a bottom plan view of FIG. 1;

FIG. 5 is a side elevation view of FIG. 1; and,

FIG. 6 is a side elevation view of FIG. 1, shown in an assembled condition on a fire hydrant.

The broken lines shown in the figures are included for the purpose of illustrating environment and form no part of the claimed design.
